INDUSTRIAL HEAT TREATING FURNACE

Clarence E. Peck, Wilkinsburg, Pa., assignor to Westinghouse Electric & Manufacturing Company, East Pittsburgh, Pa., a corporation of Pennsylvania

Application March 16, 1940, Serial No. 324,409

6 Claims. (Cl. 266—5)

This invention relates to charge-supporting hearths for heat-treating furnaces, preferably of the bell and hood type, which are to be operated at fairly high temperatures, and in which the charges are to be heat-treated while enveloped by a protective or controlled gaseous atmosphere.

It is an object of my invention to provide a relatively long hearth capable of withstanding high temperatures in the neighborhood of 1600 to 1800° F., and above, which will have provisions for permitting all the necessary differential expansions between its hot parts inside the furnace, and the cooler outer parts without damage. In this respect it is a further purpose of my invention to so construct and divide the metallic parts of the hearth so that their displacements, due to expansion and contraction, will be reduced, keeping the maximum displacement of any part to relatively small proportions. Additionally, in accordance with this aspect of my invention, the spaces between the divided parts are provided with suitable sealing or closure means.

It is a further object of my invention to provide a hearth comprising a non-metallic refractory base portion which will not chemically react, especially in a hydrogen atmosphere, with a metallic charge-supporting means which it supports.

It has been found by experience that if the metallic charge supporting means was made of an inexpensive ferrous metal, such as mild steel, the metal would react chemically with the non-metallic refractory directly supporting it, particularly during the purging of air and moisture from the furnace by a continuous flow of a controlled hydrogen atmosphere; the melting point and strength of the refractory being adversely affected. It is my opinion that as the temperature of the furnace increased, any small layer of iron oxide on the surface of the metal was reduced by the hydrogen, and if such reaction occurred where the metal was in contact with the refractory, the refractory material would fuse and melt, forming a material of a much lower melting point than the original refractory.

Accordingly, it is an object of my invention to provide a hearth of the type described which utilizes relatively inexpensive materials for the charge plate and the non-metallic supporting refractory, but which will include means for limiting the deterioration of the non-metallic supporting refractory.

It is a further object of my invention to provide means to convey the controlled atmosphere

through the hearth to the inside of the furnace, preferably inside the hood enclosing the hearth. To this end I provide suitable gas-sealing means which will enable all of the required inlet and discharge pipes to expand independently of each other, and thus I overcome a difficult expansion between parts having considerably different temperatures. All welded joints and metallic type expansion joints which may crack and fail are eliminated in my construction.

In accordance with my invention, the hearth comprises a non-metallic refractory base upon which rests a base plate made of a plurality of sections having spaced edges so that the sections may expand and contract toward and away from each other. However, a suitable means is provided covering and sealing the spaces between these edges, this means being substantially gas-tight, but not interfering with the displacement of the sections. Additionally, the outer periphery of the base plate preferably is provided with depending lips or flanges which extend into a suitable gas-sealing channel around the base portion of the refractory base, the flanges and channel being also provided with means, substantially gas-tight, which will permit these parts to expand and contract without extensive displacement. As a further novel feature of my invention, the flanges are provided with guiding means for positioning the lower edges of the furnace hood suitably in the same gas-sealing channel into which the flanges extend.

In the preferred form of my invention, the base plate takes the form of a container for holding a finely divided refractory sand, such as alumina or magnesia, which provides a sand bed that can be easily levelled. A charge-supporting plate, smaller than the container, rests on this bed, with its edges inward of the inner periphery of the container to allow for maximum changes in the dimensions of the plate with variations in temperature. A hearth, embodying a refractory sand bed confined in a container, with a charge plate resting on the bed, is described and claimed in Patent No. 2,189,624 of J. H. Bramble, issued February 6, 1940, and assigned to the Westinghouse Electric & Manufacturing Company.

Many other objects and features of my invention, and details thereof, in addition to those aforesaid, will be apparent from the following description thereof which is to be taken in conjunction with the drawings, in which:

Figure 1 is a vertical, longitudinal, sectional view of a hearth employing my invention, and

schematically showing a hood for enclosing a charge to be placed on the hearth;

Fig. 2 is a plan view of the hearth, with the hood omitted for clarity of illustration;

Fig. 3 is an enlarged fragmentary, vertical, sectional view, on the line III—III of Fig. 2, more fully showing the constructional details by which the controlled atmosphere is directed into the charge heat-treating space under the hood, a preheating conduit system being within the hearth;

Fig. 4 is an enlarged side view of a detail;

Fig. 5 is a fragmentary, vertical, sectional view, somewhat enlarged, of a modified form of hearth construction, and

Fig. 6 is a schematic, vertical, sectional view, on a much reduced scale, of a furnace incorporating my invention.

My invention is primarily applicable to a bell-type furnace such as shown very schematically in Fig. 6, although my invention is not necessarily limited to this type of furnace.

The bell-type furnace comprises a support or base 2 of a non-metallic refractory material provided with an upwardly protruding base wall portion 4 forming part of a hearth which also includes a container, indicated in its entirety by the reference numeral 6, supported on the base portion, and comprising a multi-section base plate 8 and multi-section sides 10. The container is filled with a non-metallic refractory sand 12 which can be levelled, and which supports a flat charge plate 14 on its surface, the charge plate being a single piece of suitable metal having a periphery within the inside periphery of the sides 10 and being suitably spaced therefrom at all points so that the plate may expand and contract without contacting the sides. A hearth of this general character is shown in the aforementioned patent.

A removable heating bell 16 having side wall heating elements 18 can be removably set on the base 2 which has an outside sealing channel 20 around it. This channel is filled with any suitable sealing substance for receiving a depending lip 22 of an outer metallic shell or casing 24, provided for the bell. A similar outer metallic casing 26 is provided for the outside of the base 2, so that the bell and base are rendered, as far as possible, gas-tight, as is customary in the art. The base portion 4 has a sealing means 30 around it for receiving the lower edges of a removable metallic hood or shield 32 so that any charge placed upon the hearth will be suitably enclosed within a heat-treatment space 34 defined by the hood and hearth.

In the preferred form of bell-type furnace to which my invention is applied, the heating units 18 extend below the charge plate 14 so that all parts of any charge within the heat-treatment chamber 34 will be adequately heated.

The sealing means 20 and 30 may include any suitable sealing medium, such as finely divided non-metallic refractory sand for the inner sealing means 30, and a similar sand or a suitable liquid for the outer sealing means 20.

The base portion 4 has a suitable gas inlet means schematically indicated in Fig. 6 at 36, and in greater detail in Figs. 1, 3 and 5, for a protective gas to be discharged after being preheated, along the inside surfaces of the hood.

Referring more particularly to the embodiment of my invention shown in Fig. 1, the base portion 4 is shown as comprising a continuous refractory wall which may be made of any suitable high-

temperature refractory tile, such tile usually containing relatively large percentages of silica, and perhaps magnesia or other oxides capable of resisting high temperature. Supported by the base portion 4 is the container 6 with its base plate 8 comprising a plurality of separate sections, shown in this instance as two sections 40 and 42, the facing vertical edges 44 and 46 of which are spaced from each other to provide an intervening space 48. A plate 50 has one edge welded, or otherwise secured, to the section 40 and its other edge slidable on top of the other section 42. This plate 50 covers the space 48 so that the container can be filled with sand to provide the sand bed 12. Secured to and coextensive with the other vertical edges of the sections 40 and 42 are upstanding lips or flanges 52 and 54, respectively, comprising upper portions forming the sides 10 of the container 6, and lower portions extending into the sealing means 30.

In order to render these vertical flanges substantially continuous along the space 48, suitable closing members 56 and 58 are provided on each side of the hearth, each having an end portion welded or otherwise secured to the part of the flange 52 in proximity to the space 48, with the other end portion slidably contacting the flange 54. The members 56 and 58 have outer sides which are of substantially the same height and abut the outer surfaces of the flanges 52 and 54, and have inner sides which abut the inner surfaces of the flanges 52 and 54. The inner sides of the members 56 and 58 are of a height substantially equal to the distance from the top surface of the plate 50 to the top of the flanges 52 and 54. The two sides of each of the members 56 and 58 are bridged by a cross piece so that each member is, in effect, of inverted U-shape with an inner leg shorter than the outer leg which extends into the sealing means 30.

The sealing means 30 comprises a generally U-shaped channel 60 for confining the refractory sealing sand 62 into which the flanges 52 and 54, including the outer sides of the members 56 and 58, extend, and in order to provide suitable expansion means for the channel 60 it is also split into a pair of spaced sections which are edgewise separated in the region when the container 6 is split. Insert troughs 64 and 66 bridge the space formed by the separated edges of the channel 60, these troughs closely fitting the interior surfaces of the channel 60, so as to render the latter, in effect, continuous. One end portion of each of these troughs may, if desired, be secured to one section of the channel 60, the other end portion of each trough being in slidably contacting relation with the corresponding side of the other section of the channel.

Each section of the container 6 has a freedom of movement for expansion and contraction in space 48 and the end portions of the sand seals 30, the small closure means comprising the plate 50 and the inverted U-shaped members 56 and 58 keeping the variable space 48 covered during such displacement. Additionally, the sections of the channel 60 can also expand and contract, the closure troughs 64 and 66 keeping the channel complete at all times. Consequently, the container 6 is full-floating with provisions for expanding and contracting at a plurality of points distributed along its length so that each displacement is relatively small as compared to what would have been the displacement if the container had been made solid. In other words, the movement of any part of the con-

tainer due to great variations in temperature is kept small in my novel construction.

In order to convey preheated protective atmosphere into the heat-treatment chamber 34, I prefer to provide the base portion 4 and the base 8 of the container with suitable apertures in which may be disposed the gas inlet system 36 which has means for allowing all of the necessary differential expansions and contractions between the hot inner parts of the furnace and cooler outer parts of the pipe system. To this end the outer casing 28 of the base is provided with an aperture to which is sealed, as by welding, gas inlet pipes 70. In this particular embodiment, two similar inlet systems are provided, one at each end of the container.

Each inlet pipe 70 extends through a sand sealing means comprising a cylindrical outer member 72 about the pipe 70 and cooperating therewith to form a sand sealing means for confining the sealing sand 74. Each of the sections 40 and 42 is also provided with apertures defined by stepped surfaces 76 for receiving a cover plate 78 which has a plurality of holes into which are fitted L-shaped pipes 80 which are embedded in the sand bed 12. A conduit 82 is directly below the cover plate 78, having one edge in the sealing sand 74 and projecting upwardly in proximity to the cover plate 78. Gas-tightly secured to the upper outside edge of the conduit 82 is an annular plate 84, and depending downwardly therefrom and also gas-tightly secured thereto is a cylindrical sealing member 86 extending downwardly into a sealing sand bed 88 confined in an annular sealing channel 90 about the pipe 82, the sealing channel 90 being gas-tightly secured to a section of the base 8 about the aperture for the cover plate 78. A handle bar 92 is secured across the top of the pipe section 82 so that it may be readily removed, or inserted in position.

The L-shaped pipes 80 have their longer legs substantially horizontal, the legs passing through suitable holes in the flanges 52 and 54, and terminating somewhat above and slightly outward from the inner side of the channel 88, where the protective atmosphere is discharged. A guard 96, closed at the bottom and sides, and open at the top, protects the outlets of the horizontal legs of the discharge pipes 80 and also diverts discharging gases upward. The vertical legs of the pipes 80 provide duct means for conveying the gases to the horizontal legs of the pipes from the distributing chamber below the cover plate 78 and formed therewith in conjunction with the channel 90, the sealing member 86, and the annular plate 84.

The sand bed 12 covers the pipes 80 and may be levelled to support the flat charge plate 14 in accordance with the teachings of the aforesaid Bramble patent.

In order to prevent damage to the guard elements 96 during lowering of the hood, and also to guide the hood into proper position, I provide guides 100 spaced along the flanges 52 and 54, and secured thereto, the guides having inclined upper surfaces for directing the hood evenly into the sealing channel 38.

I have found that in furnaces for heat-treating a charge in the presence of a large amount of a reducing gas such as hydrogen, a ferrous metal plate directly in contact with the supporting refractory tile caused chemical reaction between the refractory tile and the plate if the plate were made of a relatively inexpensive

ferrous metal such as mild steel. In order to prevent this reaction and to reduce the use of a large amount of expensive non-reacting heat-resistant metal, I have found that by interposing a thin sheet of non-reacting metal between the base plate 8 and the base portion 4, contamination and destruction of the refractory are avoided, or at least considerably reduced. Such sheets are indicated at 102 in Figs. 1 and 3. The sheets are, of course, suitably formed to fit the construction and configuration of the hearth, being suitably apertured for the gas inlet system and split in the middle, as shown, for expansion and contraction.

The modification of the hearth shown in Fig. 5 is similar in substantially all respects to that shown in Fig. 1, except that the base portion is constructed with piers 120 for supporting the container 8, the piers having alloy caps 122 for preventing reaction between the refractory and the mild steel base of the container.

I have found that a chromium nickel alloy containing 25% chromium, 12% nickel, balance iron, will suitably reduce the chemical reaction between the refractory tile and mild steel base plate 8 of the container in a bell furnace operating in the neighborhood from 1600 to 1800° F., and utilizing a substantially pure and fairly dry protective atmosphere of hydrogen which is maintained at a slight positive pressure higher than the pressure in the heating zone between the hood and the bell so that the gas leaks slowly through the sand seals, although it may be withdrawn in greater amounts through outlet pipes 124 when a large flow of the protective atmosphere is desired in the heat-treatment chamber 34.

While I have shown my invention in forms which I now prefer, it is obvious that many changes may be made in the details thereof and equivalents employed.

I claim as my invention:

1. A furnace for heat-treating a charge in a gaseous atmosphere, comprising a base portion, a container having a bottom and sides, said container comprising a plurality of sections supported by said base portion, relatively movable covering means for covering the spaces between said sections, a finely divided refractory bed in said container, a charge-supporting plate means on said bed, and gas conveying means comprising a plurality of pipe means embedded in said bed, each of said pipe means being associated with a different one of said sections.

2. In a furnace, the combination with a charge-supporting hearth means, of a raisable and lowerable hood cooperating therewith for providing a heat-treatment chamber in which charges are heat-treated in a controlled atmosphere; said charge-supporting hearth means comprising an elongated non-metallic refractory base portion; a container supported by said base portion, said container containing a divided material; flanges means depending from said container along its edges; a gas-sealing means comprising generally U-shaped channel means around said base portion, said channel means having gas-sealing medium therein, the bottoms of said hood and said flanges being disposed in said gas-sealing medium; said container, flange means, and channel means being formed of spaced sections for permitting expansion and contraction, and limiting the displacement thereof whereby any single displacement of said flange means in said channel means is less than

the total displacement; covering means for keeping the spaces between said sections covered at all times; conduit means for directing controlled atmosphere from outside of said heat-treatment chamber to the inside of said heat-treatment chamber, said conduit means comprising substantially horizontally arranged preheating pipe means disposed in said divided material, said preheating pipe means having gas outlets at said channel means near the lower edge of said hood and above said gas-sealing medium; and guide means for guiding said hood during lowering for positioning said hood in said channel means spaced slightly from said gas outlets.

3. In a furnace, the combination with a charge-supporting hearth means, of a raisable and lowerable hood cooperating therewith for providing a heat-treatment chamber in which charges are heat-treated in a controlled atmosphere; said charge-supporting hearth means comprising an elongated non-metallic refractory base portion, a heat-resistant metal on, and in contact with, said refractory base portion, said metal being of a type substantially chemically inert with respect to said refractory base portion in the presence of hydrogen at high temperatures; a container on, and in direct contact with, said heat-resistant metal, said container containing a divided material; flange means depending from said container along its edges; a gas-sealing means comprising generally U-shaped channel means around said base portion, said channel means having gas-sealing medium therein, the bottoms of said hood and said flanges being disposed in said sealing medium; said container, flange means, and channel means being formed of spaced sections for permitting expansion and contraction, and limiting the displacement thereof whereby any single displacement of said flange means in said channel means is less than the total displacement; covering means for keeping the spaces between said sections covered at all times; conduit means for directing controlled atmosphere from outside of said heat-treatment chamber to the inside of said heat-treatment chamber, said conduit means comprising substantially horizontally arranged preheating pipe means disposed in said divided material, and duct means connected to said preheating pipe means, said duct means opening below said container, said heat-resistant metal having an opening around said duct means, said preheating pipe means having gas outlets at said channel means near the lower edge of said hood and above said gas-sealing medium; and guide means for guiding said hood during lowering for positioning said hood in said channel means slightly spaced from said gas outlets.

4. In a furnace, the combination with a raisable and lowerable hood, of a charge-supporting hearth means cooperating therewith for providing a heat-treatment chamber in which charges

are heat-treated in a controlled atmosphere, said charge-supporting hearth means comprising an elongated non-metallic refractory base portion, a container supported by said base portion, said container comprising spaced sections and relatively movable covering means for covering the spaces between said sections, said container containing a finely divided material and comprising a base plate, conduit means for directing controlled atmosphere through said hearth means to said heat-treatment chamber, said conduit means comprising substantially horizontally arranged pipe means disposed in said finely divided material, said conduit means having gas-outlet duct means extending through said base plate to said pipe means, a gas-distributing chamber below said base plate into which said duct means opens, and gas inlet means for conveying controlled atmosphere to said gas-distributing chamber.

5. In a furnace, the combination with a raisable and lowerable hood, of a charge-supporting hearth means cooperating therewith for providing a heat-treatment chamber in which charges are heat-treated in a controlled atmosphere, said charge-supporting hearth means comprising an elongated non-metallic refractory base portion, a container supported by said base portion, said container containing a finely divided material and comprising a base plate, conduit means for directing controlled atmosphere through said hearth means to said heat-treatment chamber, said conduit means comprising substantially horizontally arranged pipe means disposed in said finely divided material, said conduit means having gas-outlet duct means extending through said base plate to said pipe means, a gas-distributing chamber below said base plate into which said duct means opens, and gas inlet means for conveying controlled atmosphere to said gas-distributing chamber, said gas inlet means comprising a gas inlet pipe having a discharge end in said gas-distributing chamber, and gas-sealing means for said discharge end permitting said inlet pipe to expand and contract.

6. A heat-treating furnace for heat-treating a charge at relatively high temperatures while the charge is enveloped by a controlled reducing atmosphere, said furnace comprising a charge-supporting means comprising a silica-containing refractory firebrick wall portion, a relatively thin heat-resistant metal in direct contact with said refractory wall, and a mild steel plate member in contact with said heat-resistant metal, said heat-resistant metal, in the presence of hydrogen at high temperatures, being substantially chemically inert with respect to the refractory of said refractory firebrick wall portion in contact therewith, said heat-resistant metal being between said refractory wall and said plate-member, whereby said plate-member and said refractory are separated.

CLARENCE E. PECK.
